LOOSE LEAF BINDER

Adolph G. Lotter, Milwaukee, Wis., assignor to
Stationers Loose Leaf Company, Milwaukee,
Wis., a corporation of Wisconsin

Application February 7, 1935, Serial No. 5,320

3 Claims. (Cl. 129—13)

This invention relates to improvements in loose leaf binders.

In certain types of loose leaf binders, the binder heads between which the body of loose leaves is clamped are expansibly connected by telescoped posts and are releasably secured against separation through the medium of small clutch balls wedged between cooperating surfaces.

The earlier ball clutches of this type were so constructed that the balls were acted upon by gravity and were held in their potentially operative positions by gravity. As a consequence, the locking means could function only with the binder in one position, namely, that position in which the balls would be maintained by gravity in their potentially operative positions. In a reverse position, the binder could not be secured closed.

To correct this difficulty, spring pressed means were provided to maintain the clutch balls in their operative positions. Patent No. 1,632,249, dated June 14th, 1927, and issued to W. J. Steenrod shows the provision of such spring means.

The present invention also provides means to yieldingly maintain the clutch balls in their operative positions, and has as an object to improve the construction of locks of this type.

Another object of this invention resides in the provision of novel and improved means for releasing the locking means to permit spreading apart of the binder heads.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention constructed according to the best mode so far devised for the practical application of the principles thereof, and in which:

Figure 1 is a top plan view partly broken away and in section showing a loose leaf binder embodying this invention, only part of the cover being shown, the view being taken on the plane of the line 1—1 of Figure 2.

Figure 2 is a partial end view of the binder, a portion of the body of leaves being broken away and in section;

Figure 3 is a view looking at the inside of the binder back, said view being taken on the plane of the line 3—3 of Figure 1 and having portions thereof broken away and in section;

Figure 4 is an enlarged detail section view showing the locking means per se; and

Figure 5 is a detailed section view taken through Figure 4 on the plane of the line 5—5.

Referring now more particularly to the accompanying drawings in which like numerals indicate like parts throughout the several views, the numerals 5 and 6 represent the two heads of the binder between which a body of leaves 7 is adapted to be clamped. The heads 5 and 6 are equipped with the usual hinged covers 8 and are expansibly connected by a back 9 composed of two slidably joined sections 10 and 11 each carried by one head, and by expansible posts 12 and 13.

The back section 10 has its opposite edges provided with inwardly directed flanges 14 to embrace the adjacent ends of the section 11, and to limit the separation of the binder heads, projections 15 and stops 16 are provided, the projections 15 being formed as part of the flanges 14 and the stops 16 being carried by the back section 11.

Both binder heads are preferably of tubular construction and each has end caps 17 between which the covers 8 are hingedly mounted.

The expansible posts 13 each comprise two telescoped tubular sections 18 and 19 fixed respectively to the binder heads 5 and 6. Contained within these telescoped tubular sections are expansive springs 20 whose ends abut the binder heads so as to at all times yieldingly urge the binder heads apart.

Acting against the springs 20 and adapted to releasably lock the binder heads against movement apart are two ball locking mechanisms indicated generally by the numeral 22, each carried by a post 12. The posts 12 comprise solid post sections 23 fixed to the binder head 6 and tubular sections 24 fixed to the binder head 5 and arranged to telescope over the solid post sections 23.

The outer end of each tubular post section 24 is taperingly reduced as at 25 to provide an inner conical surface 26 between which and the adjacent wall of the post 23 clutch balls 27 are adapted to be wedged to effect a locking action between the post sections 23 and 24.

These balls 27, four for each locking device, as best shown in Figure 5, are loosely received in radial holes 28 drilled in the outer end portion 45 of a carrier sleeve 29 telescoped within the tubular post section 24 and adapted to receive the solid post section 23.

The outer end portion of the carrier sleeve 29 has its outer surface taperingly reduced in conformance with the tapered conical inner wall 26 of the tubular post section 24.

The inner end portion 30 of the carrier sleeve projects into the interior of the hollow binder head 5 where an expansive spring 31 engages it to yieldingly urge the same into the tubular post section 24. The spring 31 is confined between the outer wall of the binder head and a cross pin 32 extending diametrically across the end portion 30 of the carrier sleeve.

The cross pin 32 also has a roller 33 journalled thereon which is adapted to ride on an inclined releasing finger 34 formed as part of a releasing bar 35 slidable longitudinally within the hollow binder head 5. To accommodate the releasing finger 34, the adjacent end portion 30 of the carrier sleeve has diametrically opposite holes 36 of sufficient size to permit endwise shifting of the carrier sleeve, which motion is translated to the carrier sleeve from longitudinal movement of the releasing bar 35 through the inclination of the releasing finger 34.

The releasing bar 35 is guided for longitudinal motion within the hollow binder head 5 and is held in its position slidably engaging the inner face of the inner wall of the binder head by a spring finger 37.

At one end the releasing bar 35 has a handle portion 38 which projects from the binder head through an opening 39 in the adjacent end cap 17.

With the releasing bar 35 positioned as shown in Figures 1 and 3, the lowest portions of the releasing fingers are in line with the posts 12 thus allowing the springs 31 to yieldingly project the carrier sleeves into their tubular post sections 24 and maintain the balls 27 in operative positions entirely independently of the position of the binder.

In other words, regardless of whether the head 5 or the head 6 is lowermost, the balls 27 are always held in their operative positions as long as the releasing bar is pushed in.

As noted hereinbefore, the balls 27 are loosely received in the holes 28 so that while the carrier sleeves act to hold the balls in potentially operative positions, there is sufficient play to allow the main springs 20 which urge the binder sections apart, to cause a slight outward relative movement between the post sections 23 and 24 when the pressure closing the binder is released. As this slight play is taken up, the balls are wedged between the inclined surfaces 26 and the post sections 23. Taking up this play also moves the balls against the peripheries of the holes 28 nearest the outer ends of the posts so that while relative outward movement of the post sections 23 and 24 is effectually prevented, the gripping action may be automatically released merely by pressing the binder heads together.

To release the gripping action and allow the binder heads to separate under action of the springs 20 contained within the posts 13, the carrier sleeves are pulled inwardly by actuating the releasing bar 35. As the releasing bar 35 is pulled out, the inclination of its releasing fingers 34 acting against the rollers 33 pulls the carrier sleeves into the binder head 5 and moves the balls 27 away from the inclined surfaces 26.

From the foregoing description taken in connection with the accompanying drawings, it will be readily apparent to those skilled in the art to which this invention appertains, that this invention provides a ball clutch locking means for loose leaf binders which is of simple and practical construction, and that by virtue of the novel means employed for releasing the gripping action, operation of the binder is materially improved.

What I claim as my invention is:

1. In a loose leaf binder, hollow binder heads, expandible means connecting the binder heads

including an expandible post having a tubular post section attached to one of the binder heads and a complementary post section telescoped within the tubular section and carried by the other binder head, an inner conical wall on the tubular post section, clutch balls adapted to be wedged between said conical wall and the complementary post section to secure the post sections against movement apart, a carrier sleeve slidable in the tubular post section and carrying the clutch balls, said carrier sleeve projecting into the hollow binder head to which the tubular post section is attached, an expansive spring yieldingly urging the carrier sleeve outwardly of the binder head to slide the same into a position maintaining the clutch balls in operative position, a releasing bar longitudinally slidable in said hollow binder head, a releasing finger on said bar having an inclined portion projecting through a hole in the carrier sleeve portion within the hollow binder head to extend diametrically across said portion of the carrier sleeve, and a cross pin carried by said portion of the sleeve to be acted upon by said inclined part of the releasing finger so that longitudinal shifting of the releasing bar draws the carrier sleeve into the binder head to withdraw the clutch balls from the conical wall and release the post sections for separation.

2. In a loose leaf binder having binder heads, one of which is hollow, connected by expandible posts, means for releasably holding the binder heads against movement apart while permitting movement thereof together, a sleeve slidable within one post in one direction to release the holding means and in the other direction to engage the holding means, one end of said sleeve projecting into the hollow binder head, a spring in said binder head acting on the sleeve to yieldingly urge the same in said second mentioned direction, a releasing bar slidable in the hollow binder head, a cam finger on said bar passing transversely through openings in the sleeve, and a cross pin carried by the sleeve for engagement with the cam finger whereby movement of the releasing bar in one direction moves the sleeve in said first mentioned direction against the action of the spring.

3. In a loose leaf binder having binder heads, one of which is hollow, connected by expandible posts, means for releasably holding the binder heads against movement apart while permitting movement thereof together, a sleeve slidable within one post in one direction to release the holding means and in the other direction to engage the holding means, one end of said sleeve projecting into the hollow binder head, a spring in said hollow binder head in line with the sleeve for yieldingly urging the sleeve in said second mentioned direction, a releasing bar slidable in the binder head, a cam finger carried by the releasing bar passing transversely through openings in the sleeve, and a cross pin carried by the sleeve for engagement with the cam finger so that movement of the releasing bar in one direction is effective to move the sleeve in said first named direction, and said cross pin being engaged by the spring to thereby transmit the force of the spring to the sleeve.

ADOLPH G. LOTTER.
